8 Claims. (Cl. 159—4)

1

Spray drying is a method quite commonly used for recovering in solid and substantially dry form a product that has been dissolved in a solvent or otherwise incorporated in a thin liquor. The basic feature of the spray-drying process resides in spraying the liquor to be dried into contact with a hot gas, heated to a temperature above the boiling point of the solvent or other liquid. The sprayed solution breaks up into finely divided droplets (i. e., becomes "atomized") so that most of the liquid volatilizes before the non-volatilized finely divided solid component reaches the bottom of the spray-drying vessel.

The present invention provides improved apparatus and an improved method for drying liquors which are related to spray-drying apparatus and methods heretofore employed, but which embody special features for overcoming some of the difficulties inherent in heretofore known apparatus and methods. One feature of the invention, for example, is the provision of apparatus more or less similar to a spray-drying vessel, but in which one or more heated and rabbed hearths are provided in the lower portion of the vessel. Spray-dried solid material falling from the upper portion of the vessel to the heated hearths is further dried as it is rabbed thereacross.

Another feature of the invention involves utilizing vapor volatilized from the liquor as the gaseous medium in which the spray-drying operation is carried out. When this feature of the invention is employed (it is particularly useful when recovery of the vapor from the liquid component of the liquor by condensation is important), provision is made for collecting at least part of the volatilized vapor, heating it to a sufficiently high temperature, and recycling it for reuse in drying a further portion of the liquor.

The advantages of the new apparatus and method will be apparent from a consideration of some of the limitations inherent in the spray-drying techniques heretofore known and employed, and which are overcome by the present invention.

In the usual spray-drying process, the liquor to be dried is sprayed into the upper part of a tall chamber, wherein it comes in contact with a current of hot gas (frequently heated air or combustion gases). The spraying head by which the liquor is introduced into the chamber atomizes it (breaks it up into fine droplets) and the resulting particles settle toward the bottom of the chamber. The liquid component is volatilized as the particles fall through the heated gas,

and the dried solid material collects at the bottom of the chamber. It is characteristic of a spray-drying operation of this sort that complete drying must take place within the time it takes for the finely divided droplets to fall to the bottom of the chamber. Some liquors do not dry very completely in this rather short time of fall, and consequently it has not been considered feasible to spray-dry such liquors economically.

The present invention meets this limitation by providing drying apparatus comprising a chamber, means for injecting into the upper portion of the chamber and atomizing a liquor to be dried, a heated hearth in the lower portion of the chamber in position to receive spray-dried material falling from the upper portion thereof, and means for rabbling the dried material on the heated hearth. A liquor to be dried is injected by spraying or otherwise into the upper portion of the chamber and therein is spray-dried sufficiently to free it from the bulk of the liquid component. The resulting partially solid particles, still moist with unvolatilized liquid, fall to the heated hearth in the lower portion of the vessel. As the moist material is rabbed or raked on the heated hearth, it is effectively freed from residual liquid. If the material is particularly difficult to free completely from residual liquid, the provision of several heated and rabbed hearths, with the rabbles arranged to rake the material successively across each hearth and from hearth to hearth, allows for heating the spray-dried material for a sufficient length of time to insure substantially complete drying.

While hearths provided in spray-drying apparatus according to the invention will most often be heated, uses are contemplated where it will be advantageous to cool, rather than heat, one or more of the hearths. Hence, while hearth-heating is frequently mentioned herein, the invention in its more general aspect contemplates maintaining the hearth or hearths at a predetermined temperature that differs from the temperature at which it or they would normally be in the absence of such means, whether such temperature maintenance or control involve heating or cooling.

Mention may be made at this point that proposals have been made heretofore to provide spray-drying equipment with rakes to move the dried material collecting at the bottom of the spray-drying chamber to a particular discharge point. So far as we are aware, however, no such proposals have involved provision of a heated or cooled hearth as herein described. It is tem-

perature control of the hearth, effected by the heating or cooling means, that leads to the improved drying or other desired results that are achieved by the invention, particularly when such temperature control is combined with a rabbling or raking action to insure substantially uniform distribution of heat through the solids collected on the hearth.

Spray-drying methods as heretofore known have been most successful for drying aqueous liquors. They have been less successful generally for drying solutions or other liquors in an organic solvent or vehicle, particularly where recovery of the volatilized organic vapor by condensation is important. One reason for this limitation is that the hot gaseous medium in which the liquor is atomized so dilutes the vapor that subsequent recovery thereof by condensation is made very difficult. Even when the gaseous heating medium is itself condensable, as when steam is employed for this purpose, condensation and recovery of the organic vapor is handicapped by the need for large condensing capacity so as to condense not only the volatilized solvent but also the steam with which it is admixed.

A feature of the present invention that provides for meeting this limitation is based on using the vapor volatilized from the liquor as the gaseous heating medium with which the solution is brought in contact for spray drying. Apparatus embodying this feature of the invention comprises a heating unit in association with the spray-drying chamber, and means for passing vapor from the spray-drying chamber through the heating unit and back into contact with additional liquor injected into the spray-drying chamber. The heated vapor serves to volatilize additional liquid from the injected liquor. It is advantageous, in apparatus embodying this feature of the invention, to provide means for separating finely divided solid or liquid particles from the vapor before the latter is heated and recycled to the spray-drying chamber. By such provision, the danger that the heating unit will rapidly become fouled by an accretion of particles of low heat conductivity is minimized.

By using liquor vapor as the gaseous heating medium, the vapor volatilized from the liquor introduced into the drying apparatus is not diluted with any foreign material. Consequently whatever part of the vapor that is not recycled may be recovered readily by condensation, with condensing apparatus of minimum capacity and cost. Contrary to what one might expect, we have found that the vapor usually need not be heated much above the boiling point of the liquid component of the liquor in order to secure effective and economical volatilization of additional vapor from the liquor in the spray-drying portion of the apparatus.

Throughout this specification and in the claims, the term "spray drying" is used. This term connotes that the liquid is atomized by being sprayed through an atomizing nozzle or spray head. We use the term, however, in a broader sense, to include any appropriate means for injecting the liquor into the apparatus. For example, instead of spraying it into the drying vessel, it may be introduced as a more or less solid stream which is broken up into small droplets by a blast of the hot gaseous drying agent or by mechanical means.

In addition to what has been described above, the invention provides a number of special fea-

tures that are advantageous in particular circumstances. One such feature involves heating the solid material on at least the lowermost of the hearths to a temperature above its melting temperature, so that the solid material is melted for convenience in handling and packing, and to insure maximum elimination of moisture, before it is withdrawn from the drying apparatus. This provision is especially useful when resins of low melting point, and which are very bulky in the spray-dried solid condition, are dried in accordance with the invention.

Another feature, of especial value when economizing on the use of heat warrants some additional investment in equipment, involves pre-evaporating the solution to be spray-dried, to concentrate it, by passing hot gas and vapors from the spray-drying operation into heat-exchange relation with the solution prior to introducing the latter to be spray-dried.

Still another feature is the provision for atomizing the solution or liquor in the spray-drying operation by directing a small stream of the solution vertically into the path of a jet of the gaseous heating medium introduced horizontally and at high velocity. This feature is particularly useful when steam is employed as the gaseous heating agent in the spray-drying operation.

In some instances it is desirable to employ in a single drying operation all of the apparatus and method features provided by the invention. For instance, when the liquor to be dried comprises an organic vehicle that must be recovered by condensation, and the spray-dried solid material is not adequately freed from residual liquid, it is generally best to make use of all features of the invention. In other cases, however, conditions may favor the use of only one of these features. For example, with liquors incorporated in a vehicle that need not be recovered, it is frequently advantageous to make use of the heated and rabbled hearths in the lower portion of the spray-drying vessel, but to effect the preliminary spray-drying operation by means of a hot gas other than the vapor of the liquid being dried. Again, there are instances when it is desirable to circulate liquor vapor through a heating unit and back into the spray-drying apparatus to volatilize additional vapor from the liquor, in accordance with the invention, but to dispense with the heated hearths.

Advantageous embodiments of the invention, in which the foregoing features are exemplified, are described below with reference to the accompanying drawings, in which

Fig. 1 is a vertical section through spray-drying apparatus constructed in accordance with the invention, taken substantially along line 1—1 of Fig. 2;

Fig. 2 is a horizontal section taken substantially along the line 2—2 of Fig. 1;

Fig. 3 is a detail showing an arrangement for sealed transferring material from an out-hearth to an in-hearth in the lower portion of the apparatus;

Fig. 4 is a diagrammatic view showing an arrangement for utilizing hot gases from the spray-drying operation to pre-evaporate and concentrate solution to be spray-dried;

Fig. 5 is a longitudinal section through apparatus arranged for recirculating liquor vapor through the spray-drying zone thereof;

Fig. 6 is a view showing another arrangement for circulating liquor vapor; and

Fig. 7 is a transverse section taken substantially along the line 7—7 of Fig. 6.

In describing the apparatus shown in the drawings, particular reference is made to drying solutions. The apparatus and method described may, however, be used equally well for drying other liquors that are not true solutions (such as thin suspensions).

The apparatus shown in Fig. 1 comprises a vessel 10, in the upper portion of which is provided a spray-drying zone 11. The vessel advantageously is made of a sheet steel or other metal shell 12, and is provided with heat insulation 13. A series of ports 14 extend around the periphery of the spray-drying zone 11. These ports provide for entry into the spray-drying zone of solution conduits 15 and steam (or other heating medium) conduits 16.

In the form of apparatus shown in Fig. 1, small steady streams of solution to be dried are fed to the spray-drying zone 11 through the solution conduits 15, and are delivered vertically downwardly directly in front of nozzle apertures 17 at the ends of the steam conduits 16. The steam (or other heating medium) is introduced under sufficient pressure so that the impact of the jet of steam issuing from the nozzles on the stream of incoming solution atomizes the latter and creates a hot turbulent atmosphere in which settlement of the atomized solution droplets is somewhat hindered. The heat of the steam or other heating medium causes the solvent to volatilize from the solution droplets, and volatilization proceeds quite rapidly in consequence of the small size and hence large surface-to-volume ratio of the droplets.

An exhaust flue 18 is provided at the top of the vessel 10. The volatilized solvent and the heating medium escape from the vessel through this flue. A damper 19 may be provided in the flue to permit some control over the flow of gas therethrough. The gas and solvent vapor withdrawn through the flue 18 may be exhausted to the atmosphere if they are inert, or, if it is desired to recover either the heating medium or the solvent, or both, they may be conducted to suitable recovery apparatus.

In the form of apparatus shown in Fig. 1, the steam jet nozzles are arranged so that they are directed horizontally substantially at right angles to a radius of the vessel 10 (and, as described, against the downwardly delivered stream of solution). This arrangement causes the atomized solution to be given a cyclonic motion within the spray-drying zone 11, which motion may be correlated with the flow of steam and vapor from the apparatus through the flue 18 to insure more uniform use of the entire volume of the spray-drying zone 11, and to minimize the amount of dried particles swept out through the flue 18 with the exiting stream of steam and solvent vapor.

A series of vertically spaced, heat-jacketed hearths 20 are mounted in the lower portion of the vessel 10 beneath the spray-drying zone 11 thereof. Three such hearths are shown in Fig. 1. Each hearth is provided with its set of rabbles (or rakes) 21 secured to rabble arms 22, which in turn are mounted on a central column 23. The column 23 is supported on a thrust bearing located below the bottom of the vessel 10, and carries a ring gear 24 through which it may be slowly rotated by suitable driving mechanism 25. The upper and lower hearths 20 are out-hearths,

that is, the rabbles 21 are set at an angle such that as the rabble arms rotate with the column 23, any solid material on these hearths is slowly raked toward their outer peripheries. The center hearth 20, on the other hand, is an in-hearth, that is, material on this hearth is advanced by the rabbles from the outer periphery toward the center of the hearth. The uppermost hearth is carried on brackets 26 which are quite short, so that spaces 27 (Fig. 2) exist between the outer periphery of the hearth and the steel shell 12 of the vessel 10 throughout the greatest part of the hearth periphery. Thus material that is raked to the outside of the upper hearth falls through the openings 27 to the central hearth. The outer periphery of the central hearth fits close to the shell 12 of the vessel 10, but its inner edge 28 is spaced from the central column 23. Consequently, material falling to this hearth and raked inwardly by the rabbles falls over the inner edge 28 to the lowermost hearth. Here the solid material is again raked toward the outer periphery, and ultimately reaches and falls through one or more suitably located discharge openings 29 at the outer periphery of this hearth.

An alternative arrangement for conveying material from the upper out-hearth to the central in-hearth is shown in Fig. 3. In this modification, the upper hearth, like the central hearth, has its outer periphery fitted closely against the steel shell 12 of the vessel. An enclosed heat-insulated chute 30 secured to the outer surface of the vessel shell 12 provides a passageway for material raked to the outside of the upper hearth to fall to the outside of the central hearth. The cross section area of the chute 30 is sufficiently small in relation to the volume of material transferred therethrough so that such material, backing up from the lower of the two hearths, substantially fills the chute. In consequence the chute is substantially blocked to the flow of gas therethrough. Chute transfer means of this sort are particularly advantageous when it is desired to prevent the gas or vapor atmosphere maintained in the spray-drying zone from flowing or diffusing into the space over the hearths below the chute, or vice versa.

As indicated above, the several hearths 20 are jacketed for heating by steam or other heating medium. In the particular construction shown in the drawings, the hearths are made up of flat, hollow metal segments, each segment being approximately one quarter of a circle. Four such segments secured together and mounted in a common plane form each hearth. Steam or other heating fluid is admitted to each segment through inlet conduits 31, and is exhausted through outlet conduits 32 (Fig. 2). Baffles (not shown) may be positioned within the interior of each hearth segment so as to direct the flow of steam to secure optimum efficiency and uniform heating of the hearths.

While jacketing the hearths as shown is a particularly satisfactory means for providing for hearth temperature control, it is not the only means available. Coils through which a heating or cooling fluid flows may be fastened to flat metal plate hearths for this purpose, or, in some cases, it may even be desired to heat electrically by resistance elements secured in heat-exchange relation to the hearths.

In apparatus of this sort it is generally desirable for the vessel 13 to be sealed as completely as possible from the atmosphere. Accordingly the outer periphery of the lowermost hearth is

connected in gas-tight relation to the vessel 12, and a cylinder 33 is connected in gas-tight relation to its inner periphery, about the opening through which the column 23 extends. The lower end of the cylinder 33 projects into an annular cup 34 fastened in gas-tight relation to the column 23. The cup 34 is filled with a suitable liquid, such as a high-boiling oil, to a level above the lowermost edge of the cylinder 33. Thus the vessel interior is effectively sealed from the outside atmosphere, without hindering rotation of the column 23, except through the openings properly provided for introducing and withdrawing materials treated or used in the apparatus, and these openings may readily be controlled by valves. It is of course evident that the cylinder 33 may be mounted on the column 23, and the cup 34 may be mounted on the lowermost hearth, instead of in the positions shown.

The spray-dried solute that settles from the upper spray-drying zone of the vessel 10 collects on the uppermost of the heated hearths 20. As it collects, it is slowly advanced by the rabbles 21 across the hearth to its outer periphery, where it falls to the central hearth. It is then raked across the central hearth, falls to the lowermost hearth, and finally is raked to the discharge opening. Because of the slow rotation of the column 23 and rabbles 22, the spray-dried material is retained on the heated hearths for an appreciable length of time. In consequence, with the hearths heated to a temperature above the boiling point of the solvent, any residual solvent which still moistens the spray-dried solute collecting on the uppermost hearth is quite completely volatilized by the time the solute is finally discharged from the lowermost hearth. The rabling action of the rabbles 21 serves to turn the material on the hearths over and over again, thus promoting effective final drying. The solid material finally discharged through the outlet 29 therefore is substantially completely dried.

The provision of the rabbled hearths at the bottom of the spray-drying zone 11 does not reduce the drying capacity of the apparatus. Although the movement of the spray-dried material across the hearths is slow, the amount of material on each hearth may be quite large, and hence the final drying capacity of the hearths may readily be made as large as the spray-drying capacity of the spray-drying zone 11.

Spray-dried material often is bulky and difficult to handle and package. For this reason (and also to insure elimination of the last traces of moisture) it is frequently desirable to melt it and cast it into convenient shapes. This is true, for example, of fossil resins that are spray-dried from hexane solutions. Accordingly it is sometimes advantageous to arrange the heating of the hearths so that the lowermost one or more hearths are maintained at a temperature above the melting point of the resin or other spray-dried material. If this is desired, it is only necessary to make the lowermost hearth in the form of a shallow pan capable of holding a body of the molten resin or other material, and to circulate a sufficiently hot fluid through its heating jacket. In the apparatus shown in Fig. 1, the cylinder 33, where it projects above the hearth surface, and the shell 12 of the vessel serve to make the lowermost hearth a pan for holding molten resin, if so desired. The discharge opening 29 may in such case be equipped with a heat-jacketed fluid-tight valve for controlling out-flow of the melted resin. If the resin is melted on one or more of the hearths, the rabbles may, if desired, be

omitted from those hearths, but often it is advantageous to retain the rabbles to facilitate mixing solid material falling from the hearth above with the molten resin.

Once a pool of molten resin or other material has been established on one or more of the hearths, the melting of additional resin, as it falls from the hearth above, is greatly expedited. Hence if the spray-dried solid product from the upper hearth or hearths is light and fluffy and difficult to melt, and if it is desired to melt it for convenience in handling and shipping or for any other reason, the procedure of melting the product on the lowermost hearth or hearths is often advantageous.

To achieve maximum heat economy in operating apparatus of the character described above, provision may be made for utilizing the hot steam (or other heating medium) and solvent vapors passing out through the flue 18 to pre-evaporate and thus concentrate the liquor that is to be spray-dried. Fig. 4 illustrates apparatus with which the spray-drying zone 11 of the vessel 10 may be combined in order to effect this economy. As shown in Fig. 4, the flue 18 is connected to a heat-exchange unit 35, which, in association with an expansion chamber 36, constitutes a pre-evaporator for fresh solution. The heat-exchanger may be of the type having tubes 37 extending between headers. Fresh solution to be concentrated is introduced through an inlet pipe 37' which delivers it to the interior of the pipes 37. The hot steam and vapor from the spray-drying zone flows through the unit 35 outside the pipes 37, thus heating the solution inside them. The steam and solvent vapor are withdrawn through a conduit 38 to a cooler or condenser 39, wherein they are condensed to liquid form. The condensed solvent and steam are delivered by a pipe 40 to apparatus for separating the solvent from the water with which it has condensed. A damper-controlled by-pass 41 may be provided to control the amount of steam and hot solvent vapor that is permitted to pass through the heat-exchange unit 35.

Heated solution from the unit 35 is delivered by a conduit 42 to the expansion chamber 36, wherein space is provided for solvent vapors to evaporate from the solution. A considerable portion of the solution may be recirculated from the expansion chamber through a conduit 43 back into the heat-exchange unit 35, to be re-heated and returned to the expansion tank for further concentration. Intermittently or continually a portion of the concentrated solution may be withdrawn from the chamber 36 through a pipe 44 to a cooler 45, wherein it may be cooled to a low enough temperature for safe storage in a tank 46. The amount of concentrated solution withdrawn through the pipe 44 is balanced by the amount of fresh solution introduced through the inlet pipe 37'.

Solvent vapor liberated in the expansion chamber 36 is conveyed by a conduit 46 to a cooler or condenser 47, from which condensed solvent may be withdrawn through a pipe 48.

The concentrated solution is pumped or otherwise delivered from the solution storage tank 46 to the solution inlet conduits 15 in the spray-drying zone 11 of the vessel 10.

By means of the arrangement shown in Fig. 4, a substantial saving of steam or other gaseous heating agent may be effected. A further small saving could be effected by pumping the warm concentrated liquor withdrawn from the expan-

sion tank through the pipe 44 directly to the solution inlet conduit 15, omitting the cooler 45 and the solution storage tank 46. This arrangement, while feasible in some cases, has the disadvantage of making the spray-drying operation quite inflexibly dependent on operation of the pre-evaporator equipment; and such inflexibility is often a disadvantage in the commercial operation of a plant employing apparatus of this character.

Concentration of the solution by pre-evaporation as described in connection with Fig. 4 requires considerable additional apparatus to that shown in Figs. 1-3, but with some solutions it is advantageous to concentrate them anyway before spray drying, as in recovering fossil resins from coal by the process described in Patent No. 2,506,300 which issued in the names of Ernest Klepetko, Philip de B. Kaye and Lester J. Hartzell, Jr. In such a case, the additional investment in plant facilities necessary to make use of the phase of the invention described in connection with Fig. 4 is mostly confined to making the pre-evaporator equipment of adequate size, and to providing the pipes and pumps for circulating the gases and solutions in the manner described.

The apparatus described above and shown in Figs. 1 to 3 is designed primarily for use with a gaseous heating medium other than solvent vapor to effect spray drying of the solution introduced through the conduits 15. For example, such apparatus may be used for drying solutions of coal resin in hexane, using steam as the heating medium in the spray-drying stage (as described in above-mentioned Patent No. 2,506,300). It may also be used with advantage where no provision is deemed necessary to recover the heating medium or the solvent vapor, as when an aqueous solution is spray-dried with steam, heated air, or combustion gases.

Fig. 5 shows a modified form of apparatus which may be used with advantage when the solvent vapor is to be recovered. This modified form of apparatus is designed to achieve circulation of solvent vapor through heating units, so that the circulated vapor serves as the sole heating medium in the spray-drying stage, or is used to reduce the amount of heating medium introduced from an external source. The apparatus shown in Fig. 5 is similar to that described above in connection with Figs. 1 and 2, in that it comprises a vessel 50 enclosing a spray-drying zone 51 in its upper portion, and having a series of jacketed, heated and rabbed hearths 52 in its lower portion. Means for introducing solution to be dried and extraneous gaseous heating medium (if any is employed), and also rabbles for the hearths 52, are provided but are not shown in Fig. 5. These elements may be constructed and arranged similarly to the corresponding parts of the apparatus shown in Figs. 1 and 2.

A major feature of the apparatus shown in Fig. 5 is the provision of a vapor exhaust conduit 53 connected to the side wall of the vessel 50 near the top of the spray-drying zone. Solvent vapor from the spray-drying zone is drawn through the exhaust conduit 53, and is blown over a heating unit 54 with which the conduit 53 connects, by means of fans 55 driven through a pulley 56. After passing through the heating unit 54, the vapor is reintroduced into the vessel 50, near the bottom of its spray-drying zone 51, through a vapor return conduit 57.

The solvent vapor withdrawn through the conduit 53 will generally be at a temperature not much above the boiling point of the solvent. As the vapor passes in contact with heating coils 58 in the heating unit 54, it is heated to a substantially higher temperature, and is reintroduced into the spray-drying zone through the conduit 57 at this higher temperature. It thereby is enabled to supply the heat of volatilization necessary for vaporizing a further quantity of solvent from freshly introduced solution to be spray-dried.

Since, in some cases, an appreciable amount of solvent may be volatilized from the spray-dried solute as the latter is rabbed across the hearths 52, a second return conduit 59 may be provided for circulating heated solvent vapor over the lowermost hearth, and upwardly from hearth to hearth. A heating unit 60 is arranged in the conduit 59 and communicates with the heating unit 54, so that the fans 55 may serve to deliver solvent vapor through both of the return conduits 57 and 59. By passing some of the vapor withdrawn through the conduit 53 through the heating coils 61 of the heating unit 60 and circulating it upwardly over the several hearths, solvent vapor liberated on the hearths is swept up into the spray-drying zone 51, and complete drying of the solid material on the hearths is facilitated. A damper 62 in the return conduit 57 at the bottom of the spray-drying zone, and a second damper 63 in the conduit 59 over the lowermost hearth, are provided to regulate the total amount of vapor recirculated through the heating units 54 and 60 by the fans 55, and to regulate the proportion of vapor delivered through the respective exhaust conduits 57 and 59.

The solvent vapor circulated through the heating units 54 and 60 and back into the spray-drying zone 51 replaces part of the gaseous heating medium that must be supplied from extraneous sources to the spray-drying zone, and in some cases may render it unnecessary to supply any gaseous heating medium from extraneous sources. In either case, the result is to reduce substantially the extent to which the solvent volatilized from the solution being spray-dried is diluted by such extraneous heating medium. The solvent vapor that is finally withdrawn from the vessel 50 (for example, through an exhaust flue—not shown—similar to the exhaust flue 18 of Fig. 1) is therefore more concentrated than it would otherwise be, and may be recovered in liquid form by condensation more readily and with less extensive condensing equipment than would be necessary were the vapor largely diluted with other gases or vapors.

A modified form of apparatus embodying similar principles to that shown in Fig. 5, but more satisfactory in many cases, is shown in Figs. 6 and 7. This apparatus, like that shown in Figs. 1 and 2, comprises a vessel 65, the upper portion of which encloses a spray-drying zone 66, and the lower portion of which houses a series of vertically spaced heated and rabbed hearths (only one hearth 67 is shown). Rabbles carried on rabble arms 68, which in turn are supported by a rotatable central column 69, serve to advance material across the hearths and from hearth to hearth in the same manner as described above with reference to Figs. 1 and 2.

The vessel 65 is provided at the top with a vapor dome 70, to which a vapor exhaust flue 71 is connected. Also connected to the dome 70 is an exhaust conduit 72 leading to the intake side of a blower 73. The blower forces vapor withdrawn through the conduit 72 through a separator 74

11

and a heating unit 75 in series, and thence back into the spray-drying zone 66.

The separator 74 is provided to separate solid and liquid particles from the vapor withdrawn through the conduit 72. Any suitable apparatus capable of serving this purpose may be employed. For example, such apparatus as is known by the trade name "Multiclon" may be used advantageously. This type of separator comprises a chamber arranged so that the vapor driven through it is rapidly whirled about, and any relatively heavy solid and liquid particles suspended in the vapor are caused to impinge on and be collected by suitably arranged collecting plates. The collected solid and liquid particles may be periodically withdrawn from the bottom of the separator.

The vapor emerging from the separating apparatus, substantially freed from solid and liquid particles in suspension, is driven by the pressure developed by the blower 73 to and through the heating unit 75, in which it comes into intimate heat-exchange contact with heating coils 76. The temperature of the vapor is substantially increased in the course of its passage through the heating unit, so that upon reintroduction into the spray-drying zone, it may provide the heat necessary for vaporizing solvent from freshly introduced solution.

Provision of the separating unit 74 in the circuit through which the vapor withdrawn from the dome 70 is passed, and before such vapor enters the heating unit 75, minimizes the likelihood that the heating coils 76 will become fouled by a deposit of such solid or liquid particles as may be entrained in the vapor. If such fouling of the heating coils should occur, and particularly if the solid and liquid particles entrained in the vapor possess low heat conductivity, the efficiency of the heating unit would soon be reduced to an uneconomically low value.

The heated vapor emerging from the heating unit 75 is reintroduced into the spray-drying zone 66 through a conduit 77 having a discharge aperture 78 at its lower extremity. Advantageously this discharge aperture is arranged to direct the reintroduced vapor in a substantially horizontal direction, and at a right angle to a radius of the spray-drying zone. Solution to be spray-dried is delivered under pressure through a conduit 79 provided with a spray nozzle 80. A spray of finely divided solution droplets issuing from the nozzle 80 is intercepted by the current of heated vapor blown out through the conduit 77, and is thereby directed into a cyclonic path of circulation within the spray-drying zone 66.

As in the case of the apparatus described above with reference to Fig. 5, the apparatus shown in Fig. 6 since it provides for utilizing solvent vapor as the gaseous heating medium in which the solution is spray-dried, minimizes the amount of gaseous heating medium that need be introduced from extraneous sources, and so reduces to a minimum the extent to which the solvent vapor is diluted. While in some cases some extraneous gaseous heating medium may have to be introduced in order to effect spray-drying at the rate desired, the amount of such extraneous gaseous heating medium is reduced proportionally to the amount of solvent vapor that is recirculated by the blower 73 through the heating unit 75. Unrecirculated solvent vapor withdrawn through the exhaust flue 71 may be condensed readily, with condensing equipment of minimum capacity, as a result of the small extent to which the vapor is diluted by extraneous gaseous heating agent.

12

In both Figs. 5 and 6, only one complete unit for heating and recirculating the solvent vapor is shown. Actually several duplicate sets of heating and recirculating apparatus may be employed in both embodiments of the invention, in order to attain increased spray-drying capacity. Fig. 7, by way of example, shows in cross section three vapor-return conduits 77, associated with three vapor-recirculating circuits and three solution inlet conduits 79. Similarly, the apparatus shown in Fig. 5 may be provided with several sets of heating units 54 and 60, and associated conduits and fans, arranged about the periphery of the vessel 50.

As indicated above in connection with Fig. 1, it may be desirable in some cases to employ spray-drying apparatus having heated hearths on which the spray-dried material collects, without making use of any vapor recirculating apparatus such as that described above in connection with Figs. 5 to 7. Use of this embodiment is generally advantageous when the solution to be dried contains a solvent such as water which it is not desired to recover, but where it is difficult to remove the final moistening amounts of solvent from the spray-dried solute. Such apparatus also may be used when the solvent vapor is to be recovered, provided it is not considered objectionable to effect such recovery from diluted solvent vapor. As indicated above by way of example, such apparatus, having the heated hearths but no provision for solvent vapor recirculation, has been used successfully in drying solutions of coal resin in hexane, where steam was employed as the gaseous heating agent in the spray-drying stage.

It is also true that in some cases it may be advantageous to effect spray drying in apparatus equipped for circulating solvent vapor through a heating unit, as described in connection with Figs. 5 to 7, but without making use of the heated hearths. This is generally so when the solvent component of the solution is to be recovered by condensation, but when it is not difficult to effect desirably complete vaporization of the solvent by spray drying alone.

In still a third class of cases, where it is desired to recover the solvent and where final complete drying of the solute is difficult, it is advantageous to employ apparatus embodying both the arrangement for recirculating solvent vapors and the heated hearths on which final complete drying of the spray-dried solute is effected. This embodiment of all of the major features of the invention may be applied successfully to drying solutions of coal resin in hexane (and other solutions behaving similarly). It has the advantage that recovery of the hexane or other solvent vapor by condensation is facilitated, and at the same time a well-dried product, that is difficult to dry adequately by spray drying alone, is obtained.

We claim:

1. Drying apparatus of the character described comprising a chamber, means for injecting into the upper portion of the chamber and atomizing therein a liquor to be dried and comprising a hot gas jet nozzle extending into the chamber and directed horizontally at right angles to a radius of said chamber and a liquor delivery pipe so positioned with respect to the jet nozzle as to deliver a small stream of the liquor perpendicularly into the path of a horizontal jet of hot gas issuing from the nozzle, a hearth in the lower portion of the chamber in position to receive spray-dried material originating in said liquor and falling from the upper portion thereof, 65 heat exchange means associated with the hearth

and adapted to effect heat transfer between said heat exchange means and said fallen material on the hearth, and means for rabbling the spray-dried material on the heated hearth.

2. Drying apparatus of the character described comprising a chamber, means for injecting into the upper portion of the chamber and atomizing therein a liquor to be dried and comprising a hot gas jet nozzle extending into the chamber and directed horizontally at right angles to a radius of said chamber and a liquor delivery pipe so positioned with respect to the jet nozzle as to deliver a small stream of the liquor perpendicularly into the path of a horizontal jet of hot gas issuing from the nozzle, a plurality of vertically spaced hearths in the lower portion of the chamber, the uppermost of the hearths being in position to receive spray-dried material originating in said liquor and falling from the upper portion of the chamber, means for heating the material on each hearth, and means for raking the material across each hearth and from hearth to hearth.

3. Drying apparatus of the character described comprising a chamber, means for injecting into the chamber and atomizing therein a liquor to be dried and comprising a gaseous heating agent jet nozzle extending into the chamber and directed horizontally at right angles to a radius of said chamber and a liquor delivery pipe so positioned with respect to the jet nozzle as to deliver a small stream of the liquor perpendicularly into the path of a horizontal jet of the gaseous heating agent issuing from the nozzle, means for withdrawing the gaseous heating agent and vapor volatilized from the liquor in the upper portion of the chamber, a heated hearth in the lower portion of the chamber in position to receive spray-dried material originating in said liquor and falling from the upper portion thereof, and means for rabbling the dried material on the heated hearth.

4. Apparatus for drying solid material dissolved in a solvent therefor comprising a pre-evaporator wherein the solution is concentrated by evaporation of the solvent, a chamber having a spray-drying zone in its upper portion, means for introducing said solution into the pre-evaporator, means for injecting and atomizing concentrated solution from the pre-evaporator into the spray-drying zone of said chamber in contact with a gaseous heating medium therein and comprising a gaseous heating medium jet nozzle extending into the chamber and directed horizontally at right angles to a radius of said chamber and a liquor delivery pipe so positioned with respect to the jet nozzle as to deliver a small stream of the liquor perpendicularly into the path of a horizontal jet of the gaseous heating medium issuing from the nozzle, means for passing the gaseous heating medium and solvent vapors from the spray-drying zone into heat-exchange relation with the solution in the pre-evaporator, and a heated and rabbed hearth immediately below the spray-drying zone of said chamber in position to receive spray-dried solid material falling from the spray-drying zone.

5. Drying apparatus of the character described comprising a chamber, means for introducing a liquor to be spray-dried into the upper portion of the chamber and for atomizing the liquor therein and comprising a hot gas jet nozzle extending into the chamber and directed horizontally at right angles to a radius of said chamber and a liquor delivery pipe so positioned with respect to the jet nozzle as to deliver a small stream

of the liquor perpendicularly into the path of a horizontal jet of hot gas issuing from the nozzle, a heating unit associated with the upper portion of said chamber, means for passing vapor volatilized from the liquor in the upper portion of the chamber through the heating unit and back into contact with additional liquor introduced into the chamber, a heated hearth in the lower portion of the chamber in position to receive spray-dried material originating in said liquor and falling from the upper portion thereof, and means for rabbling the material on the heated hearth.

6. Drying apparatus of the character described comprising a chamber, a spray-drying zone in the upper portion of said chamber, a plurality of vertically spaced hearths in the lower portion of said chamber, means for injecting into the spray-drying zone and atomizing therein a liquor to be dried, a heating unit positioned outside the spray-drying zone, means for withdrawing vapor volatilized from said liquor in the spray-drying zone from the upper portion of said zone and for passing said vapors in contact with said heating unit, and means for returning said vapor from the heating unit in part to the lower portion of the spray-drying zone above said hearths and in part to the space between two of said hearths.

7. In spray-drying apparatus of the character described, a chamber having a spray-drying zone in its upper portion and a plurality of hearths in its lower portion, means for injecting into the upper portion of the chamber and atomizing therein a liquor to be dried and comprising a hot gas jet nozzle extending into the chamber and directed horizontally at right angles to a radius of said chamber and a liquor delivery pipe so positioned with respect to the jet nozzle as to deliver a small stream of the liquor perpendicularly into the path of a horizontal jet of hot gas issuing from the nozzle means for moving solids across as least one hearth from the central portion to the periphery thereof, means for transferring material from said one hearth to the hearth next below comprising an enclosed chute connecting the space over said one hearth adjacent its periphery with space over the next lower hearth adjacent its periphery, said chute being of sufficiently small cross section area relative to the volume of solid material being transferred therethrough to said next lower hearth so that it may be maintained sufficiently full at all times of said material to prevent any substantial flow of gas therethrough.

8. Drying apparatus of the character described comprising a chamber, a spray-drying zone in the upper portion of said chamber, a plurality of vertically spaced hearths in the lower portion of said chamber, means for injecting into the spray-drying zone and atomizing therein a liquor to be dried and comprising a hot gas jet nozzle extending into the chamber and directed horizontally at right angles to a radius of said chamber and a liquor delivery pipe so positioned with respect to the jet nozzle as to deliver a small stream of the liquor perpendicularly into the path of a horizontal jet of hot gas issuing from the nozzle, a heating unit positioned outside the spray-drying zone, means for withdrawing vapor volatilized from said liquor in the spray-drying zone from the upper portion of said zone and for passing said vapors in contact with said heating unit, and means for returning said vapor from the heating unit in part to the lower portion of

the spray-drying zone above said hearths and in part to the space between two of said hearths.
